UNITED STATES PATENT OFFICE.

ADOLPHUS RIGGS, OF KENNEDY, MISSOURI.

SAW-GUMMING MACHINE.

SPECIFICATION forming part of Letters Patent No. 605,515, dated June 14, 1898.

Application filed January 31, 1898. Serial No. 668,604. (No model.)

To all whom it may concern:

Be it known that I, ADOLPHUS RIGGS, a citizen of the United States, residing at Kennett, in the county of Dunklin and State of Missouri, have invented certain new and useful Improvements in Saw-Gumming Machines, of which the following is a specification.

My present invention relates to saw-gumming machines, the advantages and construction of which will be hereinafter set forth, reference being had to the annexed drawings, wherein—

Figure 1 is a perspective view of the machine, and Figs. 2 and 3 vertical sectional views.

The object of my invention is to provide a simple and at the same time highly-efficient machine and one which will accurately gage its work.

20 The body proper of the machine consists of two sections A A, each section being formed with a downwardly-projecting leg B, having an elongated slot C therein.

From the outer corners of each of the sections A there extend upright arms D, the arms being of equal height and connected to each other by a plate E. This plate is of such dimensions that when the parts are assembled there is left a space between the inner faces 30 of sections A and the legs B of such width as to accommodate a saw-blade.

Each of the sections A has a web F formed integral therewith contiguous to one of the uprights D, and secured to the webs at their 35 proximate edges are arms G. These arms G extend out from the machine at right angles thereto and are provided with elongated slots or openings H, through which extends a bolt I, provided with a thumb-nut J. A similar 40 bolt K, having thumb-nut L, is provided for the slot C.

Mounted between each pair of uprights D is a sliding block M, the blocks being directly connected by a cross bar or head N. A threaded spindle O, working in the plate E, has its 45 lower end swiveled in the cross-bar N, and when turned serves to raise or lower said cross-bar and the sliding block M.

Journaled in the blocks M is a shaft P, 50 carrying a cutter or milling-tool Q, held in place by a washer R and nut S, the cutter be-

ing in alignment with the slot or opening between the sections A. The shaft is provided with a suitable crank T for imparting motion thereto.

55 In use the saw-blade (shown in dotted lines, Fig. 2, and full lines, Fig. 3) is placed or passed in between the sections A and the depending legs B thereof, the bolt K being so regulated as to form a support for the lower edge thereof 60 and to clamp the blade between the legs or arms. Bolt I is then adjusted so as to form a gage or stop by engaging with the forward teeth and bringing the tooth which is to be operated upon to a proper position beneath 65 the cutter. The cutter is then lowered and rotary motion imparted thereto, the cutter being fed down to the required or desired depth as the cutting progresses. When a tooth has been properly dressed, the blade is 70 drawn back slightly and the cutter elevated, when by tipping the machine relatively to the blade, or vice versa, the forward tooth will become disengaged with bolt I and the blade may again be fed forward, bringing a new 75 tooth to place beneath the cutter.

By adjusting the bolt I toward or from the cutter it will be seen that teeth of different size may be gaged and cut out, as desired. So too by elevating or lowering bolt K in the 80 slot C varying widths of saws may be held in their proper position relative to the cutter.

Having thus described my invention, what I claim is—

1. In a saw-gumming machine, the combination of a frame comprising two main sections provided with depending legs having elongated slots formed therein; a bolt adjustably mounted in said slots; a cutter mounted in the upper portion of the frame; means for raising and lowering the cutter; means for imparting motion thereto; and a gage located to one side of the cutter designed to engage the teeth of the saw-blade.

2. In a saw-gumming machine, the combination of a frame comprising two main sections provided with depending legs having elongated slots formed therein; a bolt adjustably mounted in said slots; a cutter mounted in the upper portion of the frame; means for raising and lowering the cutter; means for imparting motion thereto; slotted arms ex-

tending out from the frame at approximately right angles thereto; and an adjustable bolt mounted in said arms.

3. In a saw-gumming machine, the combination of a frame comprising two main sections A provided with depending legs B having elongated slots formed therein; a bolt mounted in said slots; slotted arms H extending out from the frame; a bolt mounted in said arms; a cutter; and means for raising and lowering the cutter, substantially as described.

4. In a saw-gumming machine, the combination of a frame comprising two main sections A provided with depending legs B having elongated slots formed therein; a bolt

mounted in said slots; uprights D extending up from sections A; a plate E connecting said sections; sliding blocks M mounted between said uprights and connected by a cross-bar 20 N; a threaded spindle working in said plate E and swiveled in the cross-bar; a shaft journaled in the blocks M; a cutter carried by said shaft; slotted arms H extending out from the frame at right angles thereto; and a bolt 25 mounted in said arms.

In witness whereof I hereunto set my hand in the presence of two witnesses.

ADOLPHUS RIGGS.
